UNITED STATES PATENT OFFICE.

HERBERT J. STRAKER, OF NORTH ATTLEBORO, MASSACHUSETTS, ASSIGNOR TO WEBSTER COMPANY, OF NORTH ATTLEBORO, MASSACHUSETTS, A CORPORA-TION OF RHODE ISLAND.

DESIGN FOR A MIRROR, BRUSH, OR SIMILAR ARTICLE.

49,470.

Specification for Design.

Patented July 25, 1916.

Application filed April 15, 1916. Serial No. 91,495. Term of patent 7 years.

To all whom it may concern:

Be it known that I, HERBERT J. STRAKER, a citizen of the United States, residing at North Attleboro, in the county of Bristol and State of Massachusetts, have invented a new, original, and ornamental Design for Mirrors, Brushes, or Similar Articles, of which the following is a specification, reference being had to the accompanying drawings, forming part thereof.

Figure 1 is a plan view of the back of a mirror, showing my design. Fig. 2 is an edge view of the same, and Fig. 3 is a fragment of the handle shown in section.

I claim—

The ornamental design for a mirror, brush or similar article, as shown.

HERBERT J. STRAKER.
